SLIVER ROLL FORMING AND DELIVERY APPARATUS

Gordon Scott Fraser, Arbroath, Angus, Scotland, assignor to Douglas Fraser & Sons Limited, Arbroath, Angus, Scotland, a corporation of Great Britain and Northern Ireland

Application February 5, 1946, Serial No. 645,637
In Great Britain December 27, 1944

3 Claims. (Cl. 19—158)

1

This invention relates to improvements in apparatus whereby sliver, for example, sliver of bast fibres, such as jute, is wound into rolls and the completed rolls are delivered one at a time to a receiver.

In one such construction in which the sliver is wound between two end discs each unitary with a half arbor, on completion of the roll, arms carrying the end discs are swung apart, thereby withdrawing the half arbors from the roll, which rolls down an inclined track to a receiving station, while the discs and half arbors return to starting position for the winding of a fresh roll.

An object of the invention is to guide the roll in its travel along the inclined track so that the roll is prevented from tilting or assuming a position oblique to the position it is to occupy at the receiving station.

With the said object I dispose at opposite sides of the inclined track guide members spaced apart a slightly greater distance than the width of the roll, said guide members being formed by plates, bars or the like constituting upstanding arms of a loaded lever, preferably a spring-loaded lever, said arms being bridged by a cross-stay extending above the inclined track in the path of the roll.

The said cross-stay may be in the form of a plate which may or may not be cambered.

It will be understood that, as the roll travels down the inclined track, it mounts and depresses the cross-stay, thereby rocking the lever in the direction towards the receiver, so that in effect, the lever arms travel parallel with the ends of the roll on its way to the receiver.

After the sliver roll leaves the cross-stay, the lever returns to its initial position, the sliver end leading back from the finished roll to the fresh stream of sliver being thrown back in the direction towards the half arbors which are about to begin the winding of a fresh roll.

The single figure of the accompanying drawing illustrates a sliver roll forming machine, showing in full lines a sliver roll in position immediately prior to ejection and in dot-and-dash lines in position after ejection.

Referring to the drawing, the sliver roll indicated in full lines at A is wound between two end discs, one of which is indicated at 10, each disc being unitary with a half arbor, indicated at 11, and carried by a hinged arm 12, the arrangement being such that, on completion of the sliver roll the hinged arms 12 are swung apart, thereby withdrawing the half arbors 11 from the roll A which rolls down an inclined track 13 to a receiving station indicated at 14.

2

The inclined track is carried by brackets 15 secured to the frame 16.

To guide the roll A in its travel on the inclined track 13, so that the roll is prevented from tilting or from assuming a position oblique to the position it is to occupy at the receiving station 14, there are disposed at opposite sides of the track 13 pivoted guide members constituted by upstanding arms, one of which is indicated at 17, of a loaded lever. Said lever is pivotally mounted at 18 on the brackets 15 supporting the inclined track 13. Each arm 17 is normally retained in raised position by a spring 19 connected at one end to a bracket 15 and at the other end to an extension 17' of the arm 17.

The arms 17 are spaced apart a distance slightly exceeding the width of the roll A and are bridged by a cross-stay, in the case illustrated in the form of a plate 20 extending above the inclined track 13 in the path of the roll A.

It will be understood that, as the roll A travels down the inclined track 13, it mounts on and depresses the plate 20, thereby rocking the lever in opposition to the springs 19, so that the upstanding arms 17 swing in the direction indicated by the arrow B.

In order momentarily to retain the arms 17 in the lowered position, indicated by dot-and-dash lines, while the roll A settles in its position on the receiver, there is provided on one bracket 15 a pivoted catch lever 21, the hooked head of which is normally in the path of movement of a projection or pin 22 on the adjacent arm 17, whereby, as the arm 17 rocks about the pivot 18, the projection 22 tilts the catch lever 21 about its pivot 23 until in the continued movement of the arm 17 the projection 22 becomes engaged in the hooked end of the lever 21.

As the roll A passes to its position in the receiving station 14, it depresses the tail end 21' of the lever 21 to release the catch, whereupon the arms 17 under the influence of the spring 19 return to initial position. The roll A is then moved endwise by mechanism which is brought into operation by a tripping device indicated at 24 and operated in known manner by the pressure of the roll A.

In order to impart an impetus to the roll A to start it on its travel down the inclined track 13, there is provided a lever 25, secured on the pivot 26 of the arm 12, which lever is bent at its free end 25' to lie across the width of the roller A.

As the arms 12 are swung apart to withdraw the half arbors from the roll A, they are also

moved downwardly about the pivots 26 in the direction indicated by the arrow C to drop the half arbors into position to receive the end of the sliver for winding another roll. By this movement of the arms 12 the bent end 25' of the lever 25 is caused to press against the periphery of the roll A to start it on its travel down the inclined track.

The upstanding arms 17 are guided in raised position by guide bars 21 projecting from the outer ends of the disc-carrying arms 12 and extending outside the arms 17.

What is claimed is:

1. In sliver roll forming and delivery apparatus the combination with a receiver, and an inclined track down which the completed roll travels to the receiver, of guide members spaced apart

a distance slightly exceeding the width of said track, said guide members including normally upstanding lever arms, and a cross-stay bridging said arms and extending above said track in the path of the roll, so as to move with the roll and thereby rock said arms in the direction towards said receiver.

2. The combination claimed in claim 1 including retaining means operable by the upstanding arms whereby momentarily to retain said arms in lowered position until the sliver roll settles in position in the receiver.

3. The combination claimed in claim 1 including auxiliary means for imparting an impetus to the sliver roll to start its movement along the track.

GORDON SCOTT FRASER.
